UNITED STATES PATENT OFFICE.

CHESTER LEROY GOLDSMITH AND BERT F. WOOD, OF WINCHESTER, NEW HAMPSHIRE.

OPERATING MEANS FOR CURTAINS.

Application filed May 19, 1928. Serial No. 279,096.

This invention relates to operating means for curtains and it is primarily an object of the invention to provide means whereby the driver of a motor driven vehicle may readily 5 operate a rear curtain to open and close the rear window or light as the occasions of practice may require and to particularly prevent interference with the driving of the car of the rays of the headlights of a following vehicle passing through the rear window with a resultant liability of causing confusion to the driver.

Another object of the invention is to provide means of this kind whereby the curtain 15 may be readily and conveniently adjusted into closed position and effectively maintained in such position, said means also permitting a ready release to allow the curtain to return to its normally open position.

The invention consists in the details of 20 construction and in the combination and arrangement of the several parts of our improved operating means for curtains whereby certain important advantages are attained 25 and the device rendered simpler, less expensive and otherwise more convenient and advantageous for use, as will be hereinafter more fully set forth.

The novel features of our invention will 30 hereinafter be definitely claimed.

In order that our invention may be the better understood, we will now proceed to describe the same with reference to the accompanying drawing, wherein:—

Figure 1 is a diagrammatic view in perspective illustrating an operating means for a curtain constructed in accordance with an embodiment of our invention;

Figure 2 is a view partly in section and 40 partly in rear elevation of the movable operating member and the parts directly associated therewith as herein embodied;

Figure 3 is a sectional view taken lengthwise on the line 3—3 of Figure 1;

Figure 4 is a sectional view taken substantially on the line 4—4 of Figure 2;

Figure 5 is a sectional view taken substantially on the line 5—5 of Figure 2.

As herein disclosed, C denotes a curtain of 50 a conventional type associated with a spring roller R which operates to normally maintain the curtain C wound therearound and in open position with respect to the rear window or light W of an automobile body, preferably of an inclosed type.

Depending from the opposite sides of the

lower or free end of the curtain C are the operating cords 1 which are directed around suitably positioned guide rolls 2 and are continued by a single operating cord 3 whereby 60 pull upon the cord 3 results in even pull upon the cords 1 to effect desired lowering of the curtain C to effectually close the rear window or light W. The cord 3 is continued through a forwardly directed conduit or 65 tubular member 4, in practice preferably comprised in the roof or top structure of the car body, said conduit 4 having its forward end terminating at a point preferably above the back of the front or driver's seat. 70

The cord 3 extends downwardly from said forward or front end of the conduit or member 4 and has its free end portion provided with an enlarged member or button 5 which is adapted to be engaged from below within a 75 block 6 extending from the inner or rear face of a plate 7. The opening 8 in this block 6 in cross section is in the fashion of a buttonhole slot with the enlarged portion 8' thereof gradually reduced in diameter from its lower 80 end towards its upper end. By this means the enlargement or button 5 may be readily and conveniently engaged with the block 6.

The plate 7 is mounted for sliding movement rearwardly of a vertically disposed 85 elongated plate 10 secured to a side wall of the car body at a point immediately adjacent to a door opening and above the back of the front or driver's seat. This plate 10 is provided lengthwise thereof with a slot 11 through 90 which is adapted to travel a forwardly disposed arm 12 formed with the lower portion of the plate 7. This arm 12 immediately in advance of the plate 10 is enlarged to provide the inner stepped shoulders 14 and 15, the 95 inner shoulders 14 being readily received within the notches 16 formed in the plate 10 at opposite sides of the slot 11 at the bottom thereof whereby when the plate 7 is pulled downwardly, the curtain C will be effectively 100 held in its position drawn across the rear window or light W to close the same against such light beams as would otherwise have a tendency to pass therethrough, such as emitted from the headlights of a following machine, which would have a tendency to cause confusion to the driver of the car.

When the arm 12 has its lower portion 110 swung outwardly to release the shoulders 14 from engagement with the plate 10, the tension of the spring roller R will result in an immediate winding up of the curtain C with

a consequent return of the plate 7 to the upper portion of the slot 11.

It is to be understood that in practice the slot 11 in the plate 10 is of a length sufficient 5 to permit requisite pull being imposed upon the plate 7 to assure sufficient unwinding or movement of the curtain C to properly close the rear window or light W.

The outer enlarged portion of the arm 12 10 is disposed on a suitable upward curvature to provide a finger piece 17 to facilitate the requisite manipulation of the plate 7 and more particularly the desired downward pull thereon.

15 Anchored to the inner face of the plate 10 is an end portion of a retractile coiled spring 18 the opposite end portion being continued by an elongated straight arm 19 which is freely disposed through a guiding block 20 carried 20 by and extending rearwardly from the plate 10. The outer or free end portion of this arm 19 is returned to provide a hooked bill 21 disposed inwardly on an angle of approximately forty-five degrees with respect to the 25 arm 19. This block 20 is provided with an open slot 22 to permit the ready application of the outer or free end portion of the arm 19 thereto and the lower portion of this slot 22 is substantially intersected by a pin 23 carried by the plate 10 with which is normally engaged the bill 21 under the inherent contraction of the spring 18.

30 The upper corner portion of the plate 7 is cut away to provide a shoulder 24 which is 35 provided with a pocket or recess 25 disposed on substantially the same angle as the bill 21. When the plate 7 is released from the lower portion of the slot 11 to permit the curtain C to rewind into open position, as the plate 7 40 travels upwardly, which will be with considerable speed, the bill 21 enters the pocket or recess 24 placing the spring 18 under increased tension thereby retarding the speed of upward travel of the plate 7 and thus preventing breakage to any of the cords 1 and 3 45 or any of the connections therefor. In other words, the spring 18 serves as a bumper for the plate 7 in its upward travel to increase the efficiency of the mechanism as a whole.

50 It is to be noted that the block 6 is positioned a distance below the upper end of the plate 7 so that when the plate 7 is in its lowered position with the arm 12 in locking engagement with the plate 10, the tension imposed on the cord 3 by the shade roller R will cause said plate 7 to assume an angle which will effectively maintain such locking engagement until the same has been manually released.

60 It is also to be noted that the portion of the side wall with which the plate 10 is associated is cut away or recessed to assure the proper operation of the plate 7 and the parts directly associated therewith.

65 From the foregoing description it is

thought to be obvious that an operating means for curtains constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as 70 limiting ourselves to the precise arrangement and formation of the several parts herein shown in carrying out our invention in practice except as hereinafter claimed.

We claim:

1. The combination with a spring roller carried shade having a pull cord, of a reciprocable latch having said pull cord attached thereto, a guide for said latch, and means for securing said latch when the same is shifted to a predetermined position in the guide, said latch when released being shifted in the guide by the spring roller of the shade as the shade is wound thereon.

2. The combination with a spring roller carried shade having a pull cord, of a reciprocable latch having said pull cord attached thereto, a guide for said latch, means for securing said latch when the same is shifted to a predetermined position in the guide, said latch when released being shifted in the guide by the spring roller of the shade as the shade is wound thereon, and means for checking the movement of the latch under the influence of the spring roller at a predetermined point in its movement along the guide,

3. The combination with a spring roller carried shade having a pull cord attached thereto, of a remote control device comprising a plate having a slot therein, a latch 105 slide longitudinally of and in the slot and designed to have said pull cord attached thereto, means for securing the latch at a predetermined point in the slot to hold said shade at a desired unrolled position, the re-rolling 110 action of the shade roller acting to draw the latch when released to the other end of said slot, and means for checking the movement of the latch in the slot adjacent the said other end while being moved thereto in the manner 115 described.

4. The combination with a spring roller mounted shade having a pull cord attached thereto, of a remote control element comprising a slotted guide member having lateral notches in the side edges of the slot at one end of the same, a latch plate designed to be arranged adjacent one face of the guide plate and to overlie said slot, a tongue carried at one end of the latch plate having a reduced portion for extension through said slot to position the tongue forwardly of the other face of the guide plate, said pull cord being adapted to be attached to said latch plate, the tongue when drawn to one end of the slot to 125

unroll said shade being designed to engage in said notches and when released from the notches being drawn to the opposite end of the slot through the rewinding action of the shade, and resilient means acting to check the too rapid return of the latch plate and tongue to said other end of the slot.

5. The combination with a spring roller mounted shade having a pull cord attached thereto, of a remote control element comprising a slotted guide member having lateral notches in the side edges of the slot at one end of the same, a latch plate designed to be arranged adjacent one face of the guide plate and to overlie said slot, a tongue carried at one end of the latch plate having a reduced portion for extension through said slot to position the tongue forwardly of the other

face of the guide plate, said pull cord being adapted to be attached to said latch plate, 20 the tongue when drawn to one end of the slot to unroll said shade being designed to engage in said notches and when released from the notches being drawn to the opposite end of the slot through the rewinding action of the shade, and a check for the return movement of the latch plate to said other end of the slot comprising a spring mounted adjacent the slot and having a portion extending into the line of movement of the latch plate for 25 engagement thereby.

In testimony whereof we hereunto affix our signatures.

CHESTER LEROY GOLDSMITH.
BERT F. WOOD.
